(57) **CLAIM**

The ornamental design for a clothes hanger holder, as shown and described.

DESCRIPTION

FIG. 1 is a perspective view of the clothes hanger holder. FIG. 2 is a front elevational view of the clothes hanger holder.

FIG. 3 is a rear elevational view of the clothes hanger holder. FIG. 4 is a left side elevational view of the clothes hanger holder.

FIG. 5 is a right side elevational view of the clothes hanger holder.

FIG. 6 is a top plan view of the clothes hanger holder.

FIG. 7 is a bottom plan view of the clothes hanger holder; and,

FIG. 8 is a perspective view of the clothes hanger holder used by a user for holding one or more metal dry cleaning hangers and/or any other type of hanger with clothes.

No claim is made to the features shown in dotted lines in FIGS. 8 and 16, which represent environmental features.

1 Claim, 6 Drawing Sheets
